UNITED STATES PATENT OFFICE

2,484,995

GOVERNOR

William H. Harstick, Richmond, Ind., assignor to
International Harvester Company, a corpora-
tion of New Jersey

Application November 7, 1945, Serial No. 627,198

4 Claims. (Cl. 318—335)

1

This invention relates to a speed governor and particularly to a speed control means for power driven devices such as cream separators or the like.

More specifically the invention concerns a novel mechanism for controlling the speed of a series wound electric motor.

It is one of the characteristics of a series wound electric motor to operate at a constantly increasing speed until the windage or load balances the motor torque. It is apparent therefore that in order to maintain the motor at a certain desired speed, the load applied would have to be constant. Whenever the load, therefore, decreases, the motor in turn will speed up causing undesirable results in operations where a constant speed is necessary. This is especially true in the application of cream separators where the quantity of milk going through the bowl is subject to change at the beginning and ending of the separating operation, and speed control over the rotation of the separating bowl is necessary. Variations in the speed of the motor may also be due to line voltage variations, temperature changes or excessive wear of the working parts of the motor. Any one of these may cause an inconsistent speed that will be detrimental to the operation performed.

Therefore, an object of the present invention is to provide an improved mechanism for controlling the speed of a series wound electric motor.

Another object is to provide an improved speed control mechanism for a series wound electric motor using air resistance as a loading and speed limiting medium.

A further object is to provide a speed governing means for a motor, the effectiveness of which can be controlled by a change in the air pressure within the governing means.

Other objects and advantages will become more readily apparent from the following detailed description when read in conjunction with the accompanying drawings, wherein:

Figure 1 is a view in side elevation of a cream separator with a sectional showing of the power drive and governing means therefor;

Figure 2 is an enlarged sectional view of the governing mechanism; and

Figure 3 is a sectional view taken along the line 3—3 of Figure 2, showing a portion of the governing mechanism.

Referring to the drawings, the numeral 10 designates a cream separator. The cream separator 10 is carried on a supporting structure 11 and 10 includes a cover 12 having discharge spouts 13 55

2

and 14. A supply can 15 has a faucet 16 through which whole milk is discharged into a well, not shown, in the cover 12. A separating bowl 17 is positioned within the cover 12 and includes a plurality of separating disks 18.

An electric motor is generally designated by the numeral 19, said motor comprising a housing 20, an armature 21 rotatably mounted on a vertical drive shaft 22, field poles 23 and 24, and a 10 series wound coil 25.

The uppermost portion of the vertical shaft 22 is journaled in a bearing member 26 supported in the housing 20, said shaft extending upwardly into the separating bowl 17 for rotatably supporting same. A cooling fan 27 is positioned on the vertical shaft 22 between the bearing member 26 and the armature 21.

The lowermost portion of the vertical shaft 22 is journaled in a bearing member 28 centrally carried in the top wall 29 of a governor housing 30. In addition, said housing 30 consists of a side wall 31 and a bottom wall 32 having a centrally located air inlet opening 33, in axial alignment with the vertical shaft 22. The housing is so constructed that there is a minimum of clearance between the outer edges of the impeller and the inner walls of the housing.

The bottom wall 32 is shaped to provide an annular channel or passage 34 at the periphery of the housing 30. This channel or passage is formed by a portion 35, of the wall 32, extending upwardly and outwardly from the housing 30 and terminating in a horizontal surface 36. A plurality of slotted discharge openings 37 are formed 35 in the surface 36 and communicate with the channel 34. A relief valve ring 38, annular in shape, extends around the outer periphery of the housing 30 and is seated upon the horizontal surface 36 thereby covering and sealing the discharge 40 openings 37.

An impeller 39, consisting of a plurality of impeller plates or vanes 40, is positioned within the housing 30, and is connected to the vertical shaft 22 for rotation therewith. The motor 19 and the governor housing 30 are suitably shock mounted by a plurality of supporting cushion members 41 and 42.

During the operation of the cream separator, as the maximum quantity of milk is fed to the 50 separating bowl, the electric motor will run at a certain desired speed. During this time the impeller will rotate within the housing but will not build up a sufficient pressure therein to unseat the relief valve from the air discharge openings. The impeller is being rotated within the housing and

the air therein is also being rotated by the impeller vanes. The only restraining medium on the impeller at this stage would be the resulting surface friction of the air on the walls of the housing. Since a minimum amount of clearance is provided between the outer edges of the impeller and the inner walls of the housing, most of the mass of air is rotating at the same speed as the impeller with a minimum of air turbulence. Thus there is little work done by the impeller at this point, and it is not effective as a governing device. As the quantity of milk fed to the separating bowl decreases or as other variables cause the motor to speed up, the impeller will rotate at a speed sufficiently high for the air pressure within the housing to unseat the relief valve from the discharge openings. The flow of air through the inlet opening and the expulsion thereof by the ends of the impeller will be a sufficient load on the motor to compensate for a decrease in the flow of milk fed to the separating means. When the pressure within the housing is sufficient to unseat the valve the mass of air which has been rotating with the impeller is forced outwardly through the discharge opening. The air which then enters through the air inlet opening must be brought up to the speed of the impeller. Bringing this mass of air up to the speed of the impeller and the resultant consumption of energy provides the load on the impeller which results in the governing action of the motor. The governor therefore is responsive to the smallest variation which might occur in the speed of rotation of the motor. Thus the motor can be operated at the same desired speed as when a full milk flow is effected and inherent speed variations of the motor will be controlled. The amount of air pressure necessary to unseat the relief valve can be regulated by changing the weight of the valve ring.

A full disclosure of the operation of the invention is apparent from the foregoing description. It is to be understood, however, that modifications can be made that do not depart from the spirit of the invention as indicated by the scope of the appended claims.

What is claimed is:

1. A cream separator having a high speed separating bowl and a high speed series wound electric motor coupled thereto for driving same, in combination, a governor comprising an impeller connected to the motor for rotation therewith, a housing associated with the impeller, said housing being provided with a wall having an air inlet opening positioned near the center of rotation of said impeller, a circumferentially extending channel formed in the housing adjacent the peripheral edges of said impeller, said channel having a discharge opening, and valve means carried by the channel and substantially sealing the discharge opening, said valve means being adapted to be displaced away from said opening upon a predetermined build-up of air pressure provided by the rotation of the impeller within the housing.

2. A cream separator having a high speed separating bowl and a high speed series wound electric motor coupled thereto for driving same, in combination, a shaft rotatable with said motor, an impeller connected to the shaft for rotation therewith, a housing associated with the impeller, said housing being provided with a wall having an air inlet opening, a circumferentially extending chan-

nel at the peripheral portion of said housing, said channel being formed with a vertically extending portion terminating in a horizontal surface, said surface having a plurality of discharge openings therein, and an annular valve means seated on said channel for sealing the discharge openings, whereby when sufficient air pressure is built up within the housing by the high speed rotation of the impeller said valve means is displaced to permit discharge of air through the discharge openings.

3. A cream separator having a high speed separating bowl and a high speed series wound electric motor coupled thereto for driving same, in combination, a shaft extending from the motor and being rotatable therewith, an impeller connected to said shaft, a housing surrounding the impeller, said housing being provided with a wall at its lower extremity, said wall being formed with a centrally located air inlet opening in alignment with said shaft, an annular channel formed around said housing at the periphery of the impeller, said channel being formed with a vertically extending portion terminating in a horizontal plane and providing a surface annular in shape, a discharge opening formed in said channel and terminating in said surface, a valve ring seated on said surface for sealing the discharge opening by the force of its own weight, whereby when sufficient air pressure is built up within the housing by the high speed rotation of the impeller, said valve ring is displaced to permit the discharge of air through the discharge opening.

4. A cream separator having a high-speed separating bowl and a high-speed series wound electric motor connected thereto for driving the same, in combination, a governor comprising an impeller connected to the motor for rotation therewith, a housing having an inner peripheral wall enclosing and concentric with said impeller, the peripheral edges of said impeller being slightly spaced from the inner peripheral wall of the housing, an air inlet in said housing, said air inlet being positioned substantially near the axis of rotation of said impeller, an air discharge opening formed in said housing substantially close to and adjacent the peripheral edges of the impeller, and valve means constructed and arranged to normally seal the discharge opening during relative low-speed rotation of the electric motor, said valve means being displaceable from the discharge opening by the air pressure within the housing during relative high-speed rotation of the motor, whereby air continually enters into said housing and is directed outwardly through the discharge opening thereby placing a load on said motor and retarding the speed of the same.
